United States Patent Office.

HENRY S. VROOMAN, OF BOSTON, MASSACHUSETTS.

Letters Patent No. 77,338, dated April 28, 1868.

IMPROVED SUPPORTS FOR PASSENGERS IN CARS.

The Schedule referred to in these Letters Patent and making part of the same.

TO ALL WHOM IT MAY CONCERN:

Be it known that I, HENRY S. VROOMAN, of the city of Boston, in the State of Massachusetts, have invented a new and improved Method of Constructing and Applying Flexible Braces or Supports for Passengers while Standing or Walking Inside Horse-Railroad Cars; and that the following is a full and exact description thereof, reference being had to the accompanying drawings, which form a part of this specification.

Figure 1, of said drawings, represents a side elevation, and

Figure 2 an end elevation of a mode embodying my improvement.

The straps or braces used at present, pending from the roof of the car, for passengers to take hold of when standing, or passing in or out of the car, have but one point of attachment above, so that persons seeking support from them are subject to be swayed forward and back when the car is started or stopped. The unstable character of these supports or braces arises from the fact that the vertical position of the strap, when hanging, naturally has to be changed to an inclination of some twenty degrees before they will constitute a horizontal support to passengers, requiring, in all, a swaying movement of some forty degrees of the lower end of the brace to constitute a support both ways, as is needed, from the reverse movements caused by the starting and stopping of the car.

To overcome this unstable and treacherous character of the supports now in use, and prevent passengers from staggering and treading upon each other in the endeavor to maintain their balance, I use the ordinary strap, formed at the middle into a loop, suitable for passengers to grasp with the hand, and attach the two ends above at separate points, so as to permanently constitute two angles—the one inclined forward and the other backward—forming a permanent support, whether the car be started or stopped, producing reverse movements.

I will more particularly describe my improvement by reference to the drawings.

A, fig. 1, is the base of two uprights, B-B, which support the horizontal rod C, to which the strap or brace D is attached.

The strap D, as will be seen, is formed into a loop at the middle, suitable to clasp with the hand, and is then crossed and fastened together just above the loop, the ends extending upwards on diverging angles, and pass over and rest upon the horizontal rod C at such distance apart as to form the required angles in the strap to constitute a brace in either direction.

The ends of the strap, after passing over and around the rod C, are riveted at f f to the vertically-inclined portions of it, and kept at the required distance apart upon the rod by means of the horizontal bar or brace, E, attached to the strap at each end, as seen in fig. 1.

The principle upon which this double-acting flexible brace is constructed may be embodied and applied in many ways. The whole middle portion of the strap, pending from the rod C, may be made to constitute one loop, or one single strap may be used, of sufficient width at the upper end to constitute a double-acting brace. Consequently,

I claim broadly as new, and of my invention, and desire to secure by Letters Patent—

A double-acting flexible passenger-support in horse-railroad cars, constructed substantially as and for the purpose herein shown and described.

H. S. VROOMAN.
